UNITED STATES PATENT OFFICE.

MAXWELL M. JONES, OF CHICAGO, ILLINOIS.

BATH-CABINET HEATER.

1,240,053.

Specification of Letters Patent. Patented Sept. 11, 1917.

Application filed October 21, 1916. Serial No. 126,932.

To all whom it may concern:

Be it known that I, MAXWELL M. JONES, a citizen of the United States, residing at Chicago, in the county of Cook and State 5 of Illinois, have invented certain new and useful Improvements in Bath - Cabinet Heaters, of which the following is a specification.

The present invention relates to an improved heater or stove designed for use 10 with bath cabinets.

It is common practice to employ within a bath cabinet a heater or stove which is operated until the air within the cabinet has 15 been sufficiently heated, or charged with the requisite amount of vapor. After the bath treatment has continued awhile and the temperature has risen considerably, the patient then extinguishes the flame. It is usual 20 for the patient to occupy a sitting position in the cabinet and to be wholly inclosed within the cabinet, only his head remaining outside. Accordingly the manipulations necessary to extinguish the heater flame are 25 made under difficulty, and are effected through the sense of feeling alone. It sometimes happens the patient's hand, leg, or foot comes into contact with the heater resulting in painful burns, or possibly an up- 30 setting of the stove, so that the cabinet is liable to be set on fire.

Such dangers and difficulties as I have mentioned are entirely overcome by the present stove. For the purpose of providing 35 an improved construction, my invention embodies means for preventing tipping or upsetting of the heater, means for protecting the patient from contact with the heater, means conveniently and positively operated 40 for extinguishing the heater flame, and means permitting the heater parts to be readily disassembled for purposes of packing or shipping. These and other objects of my invention will more fully hereinafter appear 45 from the specification and claims, and are clearly set forth in the accompanying drawings, in which—

Figure 1 is a sectional view through a bath cabinet showing a stool and heater operatively positioned therewith;

Fig. 2 is a perspective view of the heater in its entirety;

Fig. 3 is a perspective view of the upper portion of the heater, exhibiting the guard frame and flame extinguisher;

Fig. 4 is a side elevation of the several

heater parts, the guard frame being shown as removed from the base, and the pan as being removed from the guard frame;

Fig. 5 is a plan view of the guard frame 60 with burner in place; and

Fig. 6 is a sectional detail showing the locking connection between the guard frame and the base.

In Fig. 1 I have represented a bath cabinet 7, the walls of which inclose a chamber 8, over which is a cover 9 provided with a central opening 10 adapted to fit around the neck of the patient. Within the cabinet is a stool or chair 11, beneath which may be placed the heater or stove 12 which forms the subject matter of the present invention. Between the heater and stool a chain or other suitable connection 13 is arranged, being hooked, if preferred, as at 14 to the 75 stool. By this means, the patient is enabled to extinguish the heater flame at will, in the manner to be presently described.

The present heater comprises four principal elements, each of which is separable 80 from the others, to-wit, a base 15, a guard frame 16, a burner 17, and a pan 18. When operatively assembled, the parts of the heater will occupy the relative positions shown in Fig. 2, but when disassembled may 85 be separated from each other in the manner shown in Fig. 4.

The heater base 15 is provided with generally cylindrical walls 19, the lower portion of which is flared out or flanged as at 90 20. The base is closed on its upper and lower sides to provide a chambered construction, a central threaded opening 21 being formed on the upper side of the base. Into this opening may be threaded a cap 22 95 having an out-turned flanged portion 23 engageable by the fingers. By means of this cap the base chamber is entirely closed.

The guard frame 16 is formed with a ring 24 on its bottom, over which the flanged portion 23 of the cap 22 may lie to hold the guard in place upon the base. Extending radially from this ring are arms 25, preferably four in number, which take an upward turn as at 26 and support a ring 27. Extending outwardly and upwardly from the ring 27 are arms 28 preferably four in number, which carry at their extremities an enlarged ring 29. Other arms 30 extend upwardly and inwardly from the ring 29 110 and support at their extremities a top ring 31. The form of guard frame just described

affords a substantial and serviceable construction, but obviously may be somewhat varied or modified without sacrifice of utility.

5 The burner 17 is cylindrical in form and adapted to fit within the lower portion of the frame where it is supported upon the arms 25 and held in place by the arms 26 and ring 27. Within the burner may be placed a suitable absorbent material covered, if desired, by a screen or mesh 32. Alcohol or other suitable fuel may be burned to supply the necessary heat. I have shown a reducer 33 consisting of a ring adapted to cover a portion of the top surface of the burner, and this may be used, if desired, to reduce the size of the flame.

Means are provided also for extinguishing the flame and consists of a disk 34 of size 20 and shape corresponding to the top of the burner and adapted when seated thereon to smother the flame. This disk is loosely carried upon an arm 35 looped as at 36 to bear against the disk when the same is in 25 central position upon the burner. The arm 35 is coiled as at 37 around a pintle 37^a extending between the rings 29 and 31 of the guard frame, from whence it projects to provide a lever portion 38. This lever is 30 bent at one place in the form of a loop 39 and elsewhere, as at 40, is formed with another bend, its extremity 41 being shaped to provide an eye 42 to which a chain or other suitable connection may be attached. When 35 in the position shown in Fig. 3, the bend 40 of the lever 38 is arranged to engage with the ring 29 of the guard frame to limit further movement of the disk away from the burner. When, however, the chain 13 is 40 pulled to swing the lever 38 around upon the arm 30 which serves as a pivotal mounting therefor, the disk 34 is brought by a swinging movement directly over the burner so as to extinguish the flame. When the 45 disk has advanced to final position the loop 36 bears upon the disk in such a manner as to hold it tight upon the burner. The loop 39 is arranged to contact with a member 43 positioned upon the ring 29 of the guard frame, to limit further movement of the disk. In this manner, I have provided a 50 positive and ready means for effectively extinguishing the heater flame, and operable by means of the chain 13 which may be conveniently secured to the stool as at 14, in the manner shown in Fig. 1.

The pan which is of cylindrical formation is formed with an out-turned flange 19 on its upper edge. It is intended that this 55 pan may be supported upon the top ring 31 of the guard frame, the flange 19 resting directly upon the ring. In this manner, the pan is supported directly above the burner and at a suitable distance, so that the flame 60 will quickly heat to a high temperature the

liquid contained in the pan. The vapor arising from the liquid thus heated may readily disseminate throughout the cabinet. As it is common to heat medicinal preparations in the use of bath cabinets, the advantages of this construction are clearly apparent.

The operation of the present heater should readily be understood from the foregoing description. The base should be 75 filled with sand or other suitable substance which will provide a ballast for the heater. For purposes of shipment, however, the base should preferably be empty. By means of the weighted base, the heater is held securely 80 in position upon the floor, and is protected against accidental tipping or upsetting. The cap used as the connecting medium between the guard frame and the base may be readily applied. It forms a closure for 85 the base such as to prevent the loss of the ballasting material, whether it be granular, liquid, or otherwise. The guard frame construction is both simple and strong. If the ring 29 be of generous diameter, it is sufficiently removed from the flame of the 90 burner to remain comparatively cool. At the same time it will protect any object from harm which comes into dangerous proximity to the flame. The guard also serves 95 as a support and mounting for the extinguisher which, as has been explained, is readily and conveniently operated by such means as the chain shown in Fig. 1.

I claim:

1. In a bath cabinet heater, the combination of a chambered base provided on its upper side with a threaded opening, a guard frame upon the base, means for detachably securing the guard frame upon the base, 105 consisting of a flanged cap adapted to be threaded into the base opening with its flanged portion overlying a portion of the frame, the cap serving when so positioned as a closure for the base, the guard frame 110 consisting of a lower circular portion, an upper circular portion, and an intermediate widened portion secured to both the upper and lower frame portions by obliquely extending arms, and a burner of cylindrical 115 shape adapted to seat within the lower circular portion of the frame, the widened intermediate portion serving as a guard to prevent accidental contact with the burner flame, substantially as described.

2. In a bath cabinet heater, the combination of a base, a guard frame detachably secured to the base, a burner removably carried in the frame, an extinguisher for the burner flame, and a pan loosely supported 125 in the frame above the burner, the frame comprising a lower portion shaped to hold the burner against lateral movement, arms extended outwardly and upwardly from the lower portion of the frame, a circular ring 130

- carried at the arm extremities, arms projected upwardly and inwardly from the circular ring, and a top ring carried by the upper arms arranged to provide a support 5 for the pan, the flame extinguisher being pivotally mounted upon one of the frame arms and arranged to move into and out of position directly over the burner, substantially as described.
- 10 3. In a bath cabinet heater, the combination of a chambered base provided on its upper side with a threaded opening, a guard frame detachably secured to the base, a locking connection between the guard frame and the base consisting of a flanged cap arranged 15 to be threaded into the base opening with its flanged portion overlying a portion of the guard frame, and a burner removably mounted in the guard frame, substantially 20 as described.
4. In a bath cabinet heater, the combination
- tion of a burner having a substantially flat upper face, a guard frame within which the burner is positioned consisting of a lower portion within which the burner may seat, 25 arms extended outwardly and upwardly from the lower portion of the burner, a ring carried by the arm extremities, arms projected upwardly and inwardly from the ring, and a top ring carried by the upper 30 arms, and means for extinguishing the burner flame comprising a lever coiled around one of the frame arms on which it swings as a pivot, and a disk loosely carried by the lever arranged to be swung into 35 position upon the burner to smother the flame, substantially as described.

MAXWELL M. JONES.
